UNITED STATES PATENT OFFICE

STEPHEN H. HIPKINS, OF AUBURN, WASHINGTON.

SANITARY COW-TAIL HOLDER.

1,389,507.

Specification of Letters Patent. Patented Aug. 30, 1921.

Application filed February 7, 1919. Serial No. 275,579.

To all whom it may concern:

Be it known that I, STEPHEN H. HIPKINS, a citizen of the United States, residing at Auburn, in the county of King and State 5 of Washington, have invented certain new and useful Improvements in Sanitary Cow-Tail Holders; and I do hereby declare the following to be a full, clear, and exact description of the invention, such as will enable others skilled in the art to which it appertains to make and use the same.

My invention relates to improvements in devices for holding the tail of a cow against switching during the milking operation.

15 The primary object of my invention is to provide a novel form of clip for clipping the end of a cow's tail so that it may be held against switching, said clip being constructed so as to not injure the tail and in 20 such manner that accidental derangement thereof is prevented.

Another and more specific object is to provide a clip of the character described that is connected with a suitable weight member 25 and will serve in a reliable manner to hold the tails of cows in the desired position during a milking operation, the clip being constructed of spring metal and so arranged that it may be readily grasped to effect 30 clasping or unclasping of a cow tail.

The above and additional objects are accomplished by such means as are illustrated in the accompanying drawings, described in 35 the following specification and then more particularly pointed out in the claims.

With reference to the drawings, wherein I have illustrated the preferred embodiment 40 of my invention as it is reduced to practice, and throughout the several views of which 45 similar reference numerals designate corresponding parts.

Figure 1 is a perspective view of my improved clip in use,

Fig. 2 is an enlarged side elevation of my 45 improved cow tail holder,

Fig. 3 is an enlarged top plan view of the clip,

Fig. 4 is a fragmentary side elevation of the jaws of the clip,

50 Fig. 5 is a fragmentary longitudinal sectional view taken on line 5—5 of Fig. 2, and

Fig. 6 is a fragmentary vertical sectional view taken on line 6—6 of Fig. 2.

Referring to the drawings by characters 55 of reference, the numeral 1 designates as an entirety a spring gripping member or

clip that is to be secured to the tail of a cow, to a chain or other suitable flexible element connected with the member 1 and a weight member 3 which is suitably connected with 60 the flexible element 2.

The securing or gripping member 1 comprises an approximately U-shaped spring metal body portion 4 that serves as a handle and has its intermediate portion bent into 65 approximately circular form as at 5. The side arm portions 6 of the body 4 are bent back upon themselves at their free ends to provide bearings 7.

I provide in connection with the handle or 70 body portion 4 gripping jaws 8 and 9 which are provided with divergent shank portions 10 and 11 respectively. The shanks 10 and 11 are reduced at their free ends to provide apertured eyes 12 and inserted through said 75 eyes and the bearings 7 on the side arms 6 are pivoted pins 13. The shanks 10 and 11 are pivoted to one another as at 14 while the jaws 8 and 9 are disposed normally parallel to one another. The side arms 6 are nor- 80 mally extended outwardly from the portion 5 of the body in divergent planes and serve to hold the shanks 10 and 11 spaced apart sufficiently to hold the jaws 8 and 9 closed. Upon the grasping of the handle portion 4 85 and forcing of the arms 6 toward one another a corresponding movement is given to the shanks 10 and 11 and the jaws 8 and 9 are opened.

The jaw 9 is rectangular and formed integral with the shank 11. Formed on the inner face of the jaw 9 are corrugations or teeth 15 which prevent slipping of the tail of the cow from between the jaws. The jaw 8 is rectangular and provided with a rectangular elongated opening 16 therein which opening receives the jaw 9.

In use when it is desired to secure the tail of a cow, the arms 6 of the body portion 4 are pressed inwardly and the jaws 8 and 9 100 open. The tail is placed between the jaws and upon release of the arms 6 the jaws will move into gripping engagement with the tail and securely hold it against slipping. The teeth or corrugations 15 in combination with the skeleton jaw 8 securely hold the tail as will be clearly seen. By means of the weight 105 3 and flexible element 2 connecting it with the clip 1 the tail of the cow may be held in the desired position so that the switching of 110 foreign matter therefrom into a bucket of milk is prevented.

With my improved tail holder it will be seen that a completely sanitary milking operation may be had.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in the details of construction, proportion and arrangement of parts may be resorted to, when required, without sacrificing any of the advantages of my invention, as set forth.

What is claimed is:—

A cow tail holder comprising pivoted handles, integral jaws on the pivoted ends of the

handles and one of said jaws having an elongated slot extending into its respective handle, said slot adapted to wholly receive the other jaw when moved therein and the latter named jaw having a serrated face, said handles extending from their pivots in diverging planes and having openings in their free ends, pivot pins in said openings, a tension member including diverging arms having bearings at their ends to receive said pins, and a substantially circular tension portion connecting said arms. 20

In testimony whereof I affix my signature in presence of two witnesses.

STEPHEN H. HIPKINS.
